UNITED STATES PATENT OFFICE

LOUIS JENSEN, OF CHICAGO, ILLINOIS, ASSIGNOR TO UNITED AUTOGRAPHIC REGISTER CO., OF CHICAGO, ILLINOIS, A CORPORATION OF ILLINOIS

DUPLICATING MACHINE

Application filed July 2, 1929. Serial No. 289,830.

This invention pertains particularly to a duplicating machine equipped with a typewriter and adapted to the purpose of filling in multiple accounting slips, sales slips, or the like, with which continuous strips of paper are provided, these strips being taken, preferably, from a single roll.

In such a machine, it is usual to lead the strips of paper from a roll, or rolls, to suitable strip guiding and supporting means and thence across the platen, to supply means for engaging the advance end-portions of the strips, and to provide tensioning means which tend to retract the strips. The purpose of the present invention is to provide a safety-catch mechanism preferably back of the platen, which will operate automatically to engage the strips and prevent them from being withdrawn from the guiding and supporting means in case of accidental release of the advance end-portions of the strips.

The invention is well adapted for use in connection with a type of machine comprising a track upon which is mounted a carriage for movement longitudinally on the track for line-spacing purposes, said carriage having mounted thereon a transversely movable typewriter which is moved in the usual way to effect letter and word spacing. The invention is applicable, however, to other types of duplicating machines, registers, and the like.

The invention is illustrated in a preferred embodiment in the accompanying drawings, in which—

Fig. 1 is a side elevational view of a machine equipped with the invention; Fig. 2, a transverse vertical section through the bed of the machine, taken as indicated at line 2 of Fig. 1; Fig. 3, a broken longitudinal section taken as indicated at line 3 of Fig. 2; Fig. 4, a broken plan view showing brokenly an extension of the bed (reversed with reference to Fig. 3); Fig. 5, a broken vertical sectional view taken as indicated at line 5 of Fig. 4; Fig. 6, an enlarged broken sectional view taken as indicated at line 6 of Fig. 5; Fig. 7, an enlarged broken vertical section taken as indicated at line 7 of Fig. 5; Fig. 8, a broken front perspective view of the means employed at the front end of the platen for en-

gaging the advance ends of the strips of the paper, the view showing a clamping-bar in raised position; Fig. 9, a section taken as indicated at line 9—9 of Fig. 8; and Fig. 10, a section taken as indicated at line 10 of Fig. 3. 55

In the preferred embodiment which is illustrated, A designates a standard upon which is mounted a track comprising spaced rails A'; B, a carriage mounted to move longitudinally on said rails, said carriage supporting a transversely shiftable typewriter B'; C, a platen mounted between the rails A'; D, D, carbon rolls mounted at opposite sides of the track, and carrying the carbon strips D' which extend transversely 65 across the platen; E, strip supporting and guiding means mounted between the rearward extensions of the rails A'; F, a paper strip roll mounted in hangers F' depending from the rails A' and from whence paper 70 strips F' are led over the strip supporting and guiding means E of the bed; and G, safety-catch mechanism mounted in the space between the rail-extensions in cooperative 75 relation with respect to the strip supporting and guiding means E.

The standard A, the bed comprising tracks A', the typewriter carriage B, and the typewriter B', are of well known construction, and need not be described in detail. Likewise, the platen C is mounted between the rails of the bed in a well known manner on lever-mechanism C' adapted to be actuated through the medium of a link C' by means of a foot-treadle (not shown). Referring to 85 Fig. 3, it may be stated that the rear end-portion 1 of the platen is adapted to be lowered through the medium of the foot-treadle, when desired; and when this action occurs, a pair of levers 2 mounted on a rock-shaft 3 is 90 actuated to lift the clamping-bar 4 which contacts with an underlying transverse stationary bar 5 which rigidly connects the front ends of the track-rails.

The rigidly secured front cross-bar 5 is 95 equipped with studs 6 adapted to engage punch-holes with which the paper strips F' are provided. In the illustration given (Fig. 8), the studs 6 are carried by a sheet-metal member 6' which is shaped to 100

conform to the contour of the upper portion of the cross-bar 5, the member 6^a being equipped with attaching lugs 6^b which are secured to the rails A' by means of screws 6^c. The clamping-bar 4 is provided with perforations 4^c which fit freely over the studs 6 as shown in Fig. 3. The front edge 4^b of the clamping-bar serves as a tearing edge.

The paper strips usually are provided 10 with forms (not shown). At the advance end of each form, the strips are provided with a pair of punch-holes 7 which are adapted to be used in filing the slips after they have been severed from the strips. It will be understood that Fig. 3 shows the position of the strips with a set of forms in position above the platen, adapted to be filled in by means of the typewriter. In this position, the studs 6 engage the punch-holes at the front ends 15 of the forms, and the front ends of the strips are clamped by means of the bar 4. After a set of forms has been filled in, the operator depresses the treadle, which has the effect of lowering the rear portion 1 of the platen and 20 lifting the clamping-bar 4. The sheets are then in position to be drawn forward to enable a fresh set of punch-holes to be brought into engagement with the studs 6, after which the pressure on the treadle is relieved and the 25 parts are permitted, under the action of the springs employed in connection with the mechanism C', to resume the position shown in Fig. 3. The operator then tears the strips along the straight edge 4^b, thus severing the 30 duplicate slips from the strips.

Bearing in mind that the strips are under tension which tends to retract them, or draw them rearwardly, it readily will be understood that should the operator, when lifting the advance ends of the strips from the studs 6, permit them to slip, the strips might thus be violently jerked rearwardly and escape from the guiding and supporting means E. The mechanism G which will be described 40 presently is intended to prevent such accidental withdrawal of the strips from the guiding and supporting means.

The carbon rolls D are well known features in this type of machine. The carbon 50 strips are interleaved between the paper strips in the manner illustrated in Figs. 2 and 3.

The strip supporting and guiding means E, with the platen C, forms a bed over which the paper strips are drawn. The means E comprises a pair of substantial transverse rods, or bars, 8 having their ends secured in longitudinal bars 9 which are secured to the inner surfaces of the rails A'; a series of 60 transverse small guide-rolls, or rods, 10 having their ends mounted in the bars 9; and a pair of longitudinal guide-members 11 mounted on the guide-rods 10 and adjustably secured by means of set-screws 11^a. The 65 guide-bars 11 are adapted to engage the edges

of the strips of paper, so as to keep the strips properly centered.

The paper roll F is, in the illustration given, a roll made up of three strips of paper wound upon a core 12 having a shaft 12^a upon which is secured an adjustable friction device 13 having an arm 13^a which engages one of the standards E'. The strips are held under suitable tension and proper alignment by means of U-shaped rods 14 whose web-portions 14^a engage loops of the strips and whose arms 14^b are pivotally connected to the hangers F'. The hangers F' depend from the rails A' a short distance back of the standard A, and the U-shaped tensioning members 14 extend rearwardly from the hangers. Springs 14^c connect the arms 14^b to the hangers F'. The rods draw the walls of the perforations in the strips against the studs 6 and preserve proper alignment of the strips. Stops 14^d limit the drop of the members 14.

The safety-catch mechanism G, in the illustration given, comprises a pair of longitudinal bars 15 adjustably mounted on the cross-rods 8, each bar carrying a series of pivoted catch-members 16 which are adapted to underlie the strips of paper, but which tend to swing to strip-catching position. Each member 16 is in the form of a pawl 20 connected by a pivot 16^a to the corresponding bar 15. The pawl has a hole-engaging finger 16^b at the upper end and has a weighted 25 lower end 16^c.

In Fig. 5, the finger of the right hand pawl 16 is shown engaging the punch-holes 7 of the strips. This may be assumed to be the result of an accidental release of the advance ends of the strips; or it may be assumed that this front safety-catch is so positioned that it will engage a punch-hole when the advance ends of the strips are engaged by the studs 6, as shown in Fig. 3. In any event, the pivoted catches are adapted to be released from the strip-securing position automatically by the strips of paper when they are drawn forward.

To hold the paper strips in proper position so that they cannot escape the catches in the event that the paper strips are violently drawn rearwardly by the tensioning device, a series of transverse rods 17 are disposed above the path of the strips, these rods having their ends secured to the bars 9. Each rod 17 is placed in position to form a stop for the catch-finger 16^b, as shown in Fig. 5. That is, the rod acts as a stop which prevents the catch-finger from being drawn rearwardly far enough to let the finger become disengaged from the punch-hole. To enable the pivoted catches to be properly adjusted with relation to the spacing of the punch-holes of a given pair, the bars are equipped with set-screws 15^a which engage the rods 8. Thus, the bars can be shifted 115 120 125 130

laterally to effect proper spacing of the catch-fingers, so that they will be disposed beneath the paths of the punch-holes with which the strips are provided.

5 To enable the strips of paper to be threaded through beneath the rods 17, the mechanism G is equipped with a device for positively swinging the catch-members 16 to the forwardly and upwardly inclined position 10 illustrated by the two rear catch-members in Fig. 5. The device referred to comprises a forwardly and rearwardly movable bar 18 having depending lugs through which extend freely rods 18^a adapted to engage the lower portions of the pivoted catches and swing them rearwardly. The ends of the rods 18^a are mounted in slots 15^b with which the bars 15 are provided. Thus, the rods 18^a are shiftable forwardly and rearwardly and 20 support the bar 18.

The bar 18 is slidably mounted in a longitudinal guide-bar 19 which has its ends provided with perforations through which the cross-rods 8 extend freely. The bar 19 is 25 fixed in position by means of set-screws 19^a. The member 19 carries a depending lug 19^b in which is journaled a rock-member 20 equipped with a gear-segment 20^a which engages a rack 21 with which the bar 18 is equipped at its lower side. The depending arm of the rock-member 20 has connected therewith a forwardly extending rod 22 whose front end is equipped with a knob 22^a. The front end-portion of the rod is supported by a guide 23 at the front end of the bed of the machine. Thus, the knob 22^a is accessible at the front portion of the machine, as appears from Fig. 1.

When it is desired to thread the paper strips through the guides, the rod 22 is drawn forwardly, thus moving the bar 18 rearwardly and causing the cross-rods 18^a to retract the strip-engaging fingers, so as to leave open a path through which the strips 45 can be threaded. After the strips have been threaded through the machine, the rod 22 is shoved rearwardly, thus moving the bar 18 to the advance position shown in Fig. 5, leaving the catch-fingers free to automatically engage the punch-holes in case the strips are accidentally released.

Any desired number of catch-fingers may be employed. The use of means for retracting the catch-fingers to facilitate the threading of the strips through the machine is desirable, but is not essential. By employing a series of catch-fingers underneath the path of the series of punch-holes at the side of the center of the machine, the chance of the strips 55 eluding the catch-fingers is reduced to a minimum. Ordinarily, a single set of catch-fingers will suffice; but inasmuch as there is some inconvenience attached to rethreading the strips through the machine, it is preferred 60 to employ a plurality of catch-fingers asso-

ciated with each longitudinal series of punch-holes.

The use of catch-fingers adapted to protrude through the punch-holes has proven satisfactory in practice. However, any other 70 suitable form of safety-catch which is automatic in its action of arresting the retraction of the strips and which is automatically released by the strips when they are drawn forward may be employed.

The foregoing detailed description has been given for clearness of understanding only, and no unnecessary limitations should be understood therefrom, but the appended claims should be construed as broadly as permissible, in view of the prior art.

What I regard as new, and desire to secure by Letters Patent, is:

1. In means of the character set forth, a bed equipped with strip supporting and guiding means over which strips provided with punch-holes may be drawn, pins fixed to the front end of said bed for holding the advance ends of the strips, a strip-supply source, strip-tensioning means tending to retract the strips, a safety-catch mounted on said bed beneath the path of the strips and serving as a feeler and adapted to automatically engage a punch-hole in the strips in case of accidental release of the strips, said safety-catch being 95 automatically released by the strips when they are drawn forwardly, means above the strip for limiting displacement of the safety-catch when it engages a punch-hole, and means normally accessible to the operator 100 for locking said safety-catch in inoperative position.

2. In means of the character set forth, a bed equipped with strip supporting and guiding means over which strips may be drawn, means for holding the advance ends of the strips, a strip-supply source, strip-tensioning means tending to retract the strips, a plurality of feeler-fingers in longitudinal alignment mounted on said bed beneath the path of the strips and adapted to engage punch-holes and catch the strips in the event of accidental release of the strips, said feeler-fingers being automatically released by the strips when they are drawn forwardly; and manual 110 means normally accessible to the operator for throwing said feeler-fingers to into and out of operative position to enable the strips to be threaded through the strip supporting and guiding means.

3. In means of the character set forth, the combination with strip supporting and guiding means, of a pair of bars extending longitudinally of the strip supporting and guiding means, means for securing said bars in a plurality of adjusted positions transversely of said strip supporting and guiding means, and catch-members pivoted on said bars and adapted to engage punch-holes in the strips when the strips are drawn rearwardly and 130

adapted to be released when the strips are drawn forwardly.

4. In means of the character set forth, the combination with strip supporting and guiding means, of rods extending transversely of said strip supporting and guiding means, a pair of bars adjustably mounted on said rods and extending longitudinally of the strip supporting and guiding means, and catch-members pivoted on said bars and adapted to engage punch-holes in the strips when the strips are drawn rearwardly and adapted to be released when the strips are drawn forwardly.

15. 5. In means of the character set forth, strip supporting and guiding means, means for holding the advance ends of strips, a strip-supply source, strip-tensioning means tending to retract the strips, feeler-fingers each 20 pivotally mounted beneath the path of the strips, said feeler fingers having weighted members normally holding the fingers in contact with the lower strip and serving automatically to cause the finger to enter a punch-hole when the finger encounters the punch-hole, and a transverse rod disposed above the path of the strips and adapted to be engaged by the feeler fingers when the latter are in their strip-catching positions.

30. 6. In means of the character set forth, the combination with strip supporting and guiding means, of a pair of bars extending longitudinally of the strip supporting and guiding means, means for securing said bars in a plurality of adjusted positions transversely of the strip supporting and guiding means, catch-members pivoted on said bars and adapted to engage punch-holes in the strips when the strips are drawn rearwardly and 40 adapted to be released when the strips are drawn forwardly, slidably mounted bars, rods carried by said slidably mounted bars and engageable with the catch-members to hold them in functionally inoperative positions, and means for reciprocating said slidably mounted bars.

7. In means of the character set forth, the combination with strip supporting and guiding means, of a pair of bars extending longitudinally of the strip supporting and guiding means, means for securing said bars in a plurality of adjusted positions transversely of the strip supporting and guiding means, catch-members pivoted on said bars and 55 adapted to engage punch-holes in the strips when the strips are drawn rearwardly and adapted to be released when the strips are drawn forwardly, slidably mounted bars, rods carried by said slidably mounted bars and engageable with the catch-members to hold them in functionally inoperative positions, and means including a rack and pinion for displacing said slidably mounted bars.

65. 8. In means of the character set forth, the combination with strip supporting and guid-

ing means, of pivotally mounted catch-members adapted to engage punchholes in the strips when the strips are drawn rearwardly and adapted to be released when the strips are drawn forwardly, slidably mounted bars, 70 means carried by said bars for engaging said catch-members and holding them in functionally inoperative positions, and means including a rack and pinion for displacing said slidably mounted bars. 75
